STUFFED TOY FOX

David J. Carlson, 1504 Inverness Court,
Naperville, Ill. 60540

Filed Feb. 4, 1974, Ser. No. 439,228

Term of patent 7 years

Int. Cl. D21—01

U.S. Cl. D34—2 R

FIG. 1 is a front perspective view of a stuffed toy fox showing my new design;

FIG. 2 is a side perspective view thereof;

FIG. 3 is a rear elevational view thereof.

I claim:

The ornamental design for a stuffed toy fox, as shown.
